UNITED STATES PATENT OFFICE

JOHN EDMAN, OF MINNEAPOLIS, MINNESOTA, ASSIGNOR TO MASTERBILT MOTOR COMPANY, OF MINNEAPOLIS, MINNESOTA, A CORPORATION OF SOUTH DAKOTA

INTERNAL AIR COOLED EXHAUST VALVE

Application filed March 28, 1930. Serial No. 439,645.

This invention relates to improvements in air cooled valves intended for general use but especially well adapted for use as an exhaust valve for internal combustion engines and more particularly such an engine that is air cooled. The primary object of the invention is to produce an air cooled valve that will keep the valve head cool throughout its full area to prevent carbon, warping and burning, that is comparatively inexpensive to manufacture and that will not leak compression at the stem connection therewith, and that can be used in connection with either an L-type or overhead type.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view of the improved valve in central longitudinal section;

Fig. 2 is a view partly in bottom plan and partly in section taken on the line 2-2 of Fig. 1;

Fig. 3 is a view partly in plan and partly in section taken on the line 3-3 of Fig. 1;

Fig. 4 is a view corresponding to Fig. 1 with the exception that the major portion of the valve stem has been broken away and that said stem has not been welded to the valve stem; and

Figs. 5 and 6 are fragmentary detail views in section showing different ways of forming grooves in the joint between the valve stem and valve head.

Referring first to the invention as shown in Figs. 1 to 4, inclusive.

The numeral 7 indicates a valve head having a flat top and a beveled peripheral face 8 which rests on a valve seat therefor, not shown. Formed in the valve head 7 inward of its face 8 is a large annular recess 9 that is concentric to said face and which recess materially decreases the thickness of the valve head 7. The surface 10 between the face 8 and recess 9 is beveled to a pitch somewhat less than that of the face 8 to more clearly

define said face and facilitate the grinding thereof.

The valve stem 11 is made independent of the valve head 7 and is in the form of a tube having a constant diameter except at its inner end portion where the same flares to form a neck 12. Integrally formed on the outer end of the neck 12 is an annular flange 13 having a width which substantially corresponds to the depth of the recess 9 and which forms an axial extension of the neck 12 and is concentric to the stem 11.

Within the valve stem 11 is a central longitudinally extended partition 14 the outer end of which is curved laterally and merges with the adjacent side of the stem 11 to close the outer end of the passageway 17 to the passageway 16. The inner end of the partition 14 extends into the neck 12 and terminates substantially at the longitudinal center thereof to leave within the outer end portion of the neck 12, the flange 13 and head 7 an air expansion chamber 15 which connects the long air passageway 16 and the short air passageway 17 formed by the partition 14. The passageway 16 extends the full length of the stem 11 and connects the outer end thereof with the air expansion chamber 15.

In the side of the stem 11 at the outer end of the air passageway 17 is an air port 18 which connects the expansion chamber 15, through the short air passageway 17, with the exterior of the valve stem 11. The air port 18 has an air-conducting capacity which is equal, at least, to that of the passageway 17.

Both sides of the inner end portion of the partition 14 within the neck 12 are curved toward diametrically opposite sides of said neck to afford diverging deflecting surfaces 19.

The flange 13 is telescoped into the recess 9 with a tight fit and a V-shaped groove 20 is formed in the outer portion of the joint between the head 7 and flange 13 which is filled with a welding material 21 that rigidly connects the valve head and stem.

Figs. 5 and 6 show different ways of forming the groove 20 to receive the welding material 21.

It will be understood that air is induced in the valve stem by a fan or any other suitable means but for the purpose of this case it will not be necessary to consider the same.

15 The circulation of air through the air passageways 16 and 17 and the expansion chamber 15 may be in either direction, to wit: through the air passageway 16, expansion chamber 15, air passageway 17 and port 18, or, 10 in reverse order. When cold air enters the chamber 15 and comes in contact with the hot valve head 7 it is heated thereby and expands in all directions over the internal surface of the valve 7, neck 12 and flange 13 and 15 produces an air circulation that carries the heat laden air to the exterior of the stem either through the outer end of said stem or through the port 18 depending upon which way the air is circulating. The deflecting 20 surfaces 19 direct the air to the far sides of the air expansion chamber 15 and thereby prevent the same from circulating from one air passageway 16-17 to the other without passing over the entire surface of the valve 25 head.

In welding the valve stem to the valve head said head is placed on a support with its stem in an upright position and the flange 13 securely holds the stem in the valve head in 30 axial alignment therewith. During the welding of the valve stem 11 to the valve head 7 the welding material will flow in the groove 20 and rigidly connect said stem and head and at the same time leave the joint therebetween in a neat and finished appearance. 35 This method of connecting the valve stem to a valve head eliminates all danger of compression leakage for the reason that there is no joint in the valve head or its face that is exposed to the force of compression.

40 What I claim is:

1. A two-part valve of the class described including a head having a peripheral face and an axial recess concentric with said face, 45 and a tubular stem the inner end portion of which is telescoped into said recess and welded to the head.

2. A two-part valve of the class described including a head having a peripheral face, 50 and an axial recess concentric with said face, and a tubular stem the inner end portion of which is telescoped into said recess, and a groove in the outer edge portion of the joint between the head and stem, and a welding 55 material in said groove rigidly connecting the head and stem.

3. A two-part valve of the class described including a head having a peripheral face and an axial recess concentric with said face, and 60 a tubular stem having a flaring neck and an axially extended annular flange on the neck tightly fitted in said recess and rigidly secured to the head.

4. A two-part valve of the class described 65 including a head having a peripheral face

and an axial recess concentric with said face, and a tubular stem having a flaring neck and an axially extended annular flange on the neck tightly telescoped in said recess and rigidly secured thereto.

5. A two-part valve of the class described including a head having a peripheral face and an axial recess concentric with said face, and a tubular stem having a flaring neck and an axially extended annular flange on the neck tightly telescoped in said recess, a groove in the outer edge portion of the joint between the head and flange, and a welding material in the groove rigidly connecting the head and flange.

6. A valve of the class described having a tubular stem, a longitudinal partition in the stem dividing said stem into a long air passageway and a short air passageway, an air expansion chamber at the inner end of the stem connecting said two passageways, and a port in the stem at the outer end of the short air passageway.

7. The structure defined in claim 6 in which the partition has in one of the air passageways an air deflecting surface.

8. The structure defined in claim 6 in which the partition has in each air passageway an air deflecting surface.

9. A two-part valve of the class described including a head having a peripheral face and a large axial recess concentric with said face, and a tubular stem having on its inner end a flaring neck and an axially extended annular flange on said neck that is concentric with the stem, said flange being telescoped into said recess and welded to the head, said stem having a longitudinally extended partition dividing the stem into a long air passageway and a short air passageway, said stem having a port at the outer end of the short passageway, and an air expansion chamber in the stem at the head connecting said two passageways.

In testimony whereof I affix my signature.

JOHN EDMAN.
